[57] CLAIM

The ornamental design for a ventilated toilet seat and cover, as shown and described.

DESCRIPTION

FIG. 1 is a perspective view taken from the top, front and right side of a ventilated toilet seat and cover showing my new design, with the cover in an open position; FIG. 2 is a front elevational view thereof showing the cover in its closed position;

FIG. 3 is a rear elevational view of FIG. 2;

FIG. 4 is a left side elevational view of FIG. 2;

FIG. 5 is a right side elevational view of FIG. 2;

FIG. 6 is a top plan view of FIG. 2; and,

FIG. 7 is a bottom plan view of FIG. 2.

It is to be understood that the conventional electric cord is shown broken away in FIGS. 1 through 7 for convenience of illustration.

FIG.1

FIG. 2

FIG. 3

FIG. 4

FIG. 5

FIG. 6

FIG. 7
